UNITED STATES PATENT OFFICE.

MICHAEL D. MALONEY, OF HONOLULU, TERRITORY OF HAWAII.

SHAFT-FINISHING TOOL.

Application filed May 20, 1926. Serial No. 110,522.

This invention relates to improvements in tools for finishing and refinishing shafts, crank pins, and like parts and is especially designed for use in refinishing the crank 5 shafts of engines of motor vehicles and also for steam engines wherein the shaft or crank pins have been worn flat, out of round, tapered or for any other reason are required to be trued and refinished or reduced in diameter.

One of the objects of the invention is the provision of a tool of this type wherein the shaft or other machine element to be operated upon is firmly held from rotation entirely independently of the mounting of the cutting tool whereby the depth of cut of the latter may be accurately regulated and the same may be also moved in a plane perpendicular to the direction of feed for the purpose of utilizing substantially the entire area of the finishing tool.

A further object is the provision of a finishing tool embodying such features of construction which ensure the abrading, cutting or other tool, utilized in finishing, remaining in proper relation to the bearing surfaces of the shaft or pin.

A further object is the provision of a refinishing tool in which one of the bearing 30 faces for the shaft is constituted by an adjustable tension bar which is capable of such adjustment as to vary pressure on the shaft and which, when adjusted to another position permits of quick and convenient detachment of the tool from the shaft.

In the accompanying drawing wherein an approved embodiment of the invention is illustrated,

Fig. 1 is a longitudinal sectional view 40 through the finishing tool showing the same applied to use.

Fig. 2 is an end elevation of the tool showing a portion of the crank shaft.

Figs. 3 and 4 are rear and edge views, respectively, of the guiding and feeding plate for the abrading block or cutting tool.

Fig. 5 is a fragmentary side elevation of the tool, partly in section, illustrating the use of a cutting tool in operative relation to the shaft to be operated upon, and replacing the abrading block illustrated in Fig. 1.

Fig. 6 is an elevation of the cutting tool.

Fig. 7 is a similar view of a modification.

Fig. 8 is an enlarged sectional view taken 55 on line 8-8 of Fig. 6.

Referring to the drawing in detail, the

numeral 5 is the body of the tool which is substantially U-shaped and includes the two parallel uprights 6 and 7 and the web portion 8. The upright member 7 is preferably hardened so as to increase its resistance to wear, and it is also preferably provided with a groove 7^a furnishing a seat for a hardened steel block 7^b, to serve as a bearing block and to make provisions for renewals, or blocks 60 of different thicknesses. The web portion 8 is recessed at 9 to accommodate a bearing block 10 having its upper surface 11 disposed obliquely to and substantially facing the inner surface of the upright 7. The top and 65 bottom faces of the block 10 are parallel so the block may be reversed.

A tension bar 12 is pivotally connected at one extremity to the upright 6 by a screw 13 and its opposite extremity (which is inclined upwardly from the upright 6) is apertured and extends across and in spaced relation above the upper extremity of the upright 7, the adjusting screw 14 being inserted in the aperture of said bar and in a 70 threaded recess in the upright 7, for a purpose which will hereinafter appear.

The shaft, crank pin or other cylindrical machine element 15 to be finished is pressed into the space between the uprights 6 and 7 75 subsequent to the removal of the screw 14 and swinging the tension bar 12 to one side so as to allow the insertion of said shaft in place, and said tension bar is thereafter swung to a position overlying the shaft 15, 80 and the screw 14 is threaded into the recess in the upright 7 and turned until the desired pressure is exerted by the tension bar 12 on the shaft 15, thus bringing the latter into contact with the blocks 7^b and 10. The 85 tension bar 12 is preferably formed of resilient material in order that the tension exerted thereby may be readily varied by proper adjustment of the screw 14 and, it

is clearly evident from Fig. 1 that the three 90 points of contact between the shaft 15 and the block 7^b, block 10 and tension bar 12 are substantially equidistant and hence a complete bearing for said shaft is provided, preventing radial displacement in any direction. It is further evident, that due to the 100 inclination of the face 11 of the bearing block 10, and the possibility of adjustment of the tension bar 12, the finishing tool is adapted for finishing shafts and pins varying to a great extent in diameter.

105 A hollow feed screw 16 is fitted in a

threaded aperture 17 provided in the upright 6, and is provided at its outer extremity with a polygonal head 18 for facilitating application thereto of a wrench. The 5 stem 19 of a guide and feed plate 20 extends through the bore of the hollow sleeve 16 and is secured in position by a nut 21 fitted on the threaded outer extremity of the stem. The inner face of the feed and guide plate 10 20 is arranged in accurate parallel relation to the bearing face of the block 7^b, so as to ensure corresponding parallel relation of the abrading block 22 to the axis of the shaft 15 to be operated upon.

15 The block 22 is disposed in sliding contact with the inner face of the plate 20 and abuts the inner threaded extremity of a handle 23 which depends from the web portion 8 of the body of the tool, and is fitted 20 in a threaded aperture 24 provided therein directly underneath the block 22. The handle 23 is of such length as to afford the necessary leverage for conveniently turning the tools bodily about the shaft 15, for finishing 25 the surface of the handle, or if preferred, for retaining the tool in fixed position while the shaft is rotated.

When the tool has been applied to a shaft 15 in the manner above described, the finishing 30 block 22 is slowly advanced until it is brought into contact with the surface of said shaft, by proper adjustment of the sleeve 16, and as the tool is turned about the shaft and the finishing of the surface 35 thereof progresses, the handle 23 is turned so as to advance the block 22 along the shaft 15 and utilizes substantially the entire area of the block in finishing said shaft. As the shaft is turned down to a true surface, the 40 block 22 is readjusted by further adjustment of the sleeve 16. In the case of repairing or refinishing a shaft having a flat spot, the abrading block 22 will not remove an undue amount of metal. Although, if 45 a high spot is present on the shaft either at the bearing point on the upright 7 or directly opposite at the block 22, this high spot will be removed.

Due to the manner of mounting the block 50 22, the latter may be removed and replaced end for end and back and front as the faces thereof become worn, and the corners of said block are preferably rounded and, as will be understood, an abrading material 55 having slow or fast cutting qualities may be employed as the condition of the shaft or its degree or hardness may require.

When the surface of the shaft 15 is worn or injured to such an extent as to render 60 refinishing by an ordinary abrading stone or block 22 tedious and difficult, a metallic block 26 having a groove 26^a is employed, (see Fig. 5). This groove receives a removable cutting tool 26^b, which is made of 65 metal. This tool has a curved cutting edge

26^c which is highest at the central portion of the tool. The face 26^d of this tool is parallel with the rear face 26^e of the tool. Due to this construction, the longitudinal center of the cutting edge, when the tool is 70 used, will first come into contact with the shaft. The upper face of the tool is provided with a curved groove 26^f, the bottom of which is highest at the longitudinal center of the tool, so that shavings lodged 75 in the groove will move towards the ends of the latter and be automatically discharged. The block 26 which carries this tool is secured to the plate 20 by screws 27 which extend through slots 28 in the plate 80 20 and enter threaded apertures in the block. Due to this construction, the block may be moved up and down relatively to the plate 20, this movement being limited by ends of the slots 28. The tool 26^b is secured to the block by a threaded rod 31 which threads into the block at 32 and is provided with a pointed end which enters a conical recess 33 on the under side of the tool. This rod extends through the hollow handle 23 and is provided at its lower end with threads engaged by a lock nut 33^a. When the lock nut is loosened, the rod 31 may be fed side wise in the handle.

Instead of using the tool shown in Figs. 6 and 8, I may, when desired, employ the tool 35 shown in Fig. 7, this tool being made of hard metal and having inclined teeth 36 on one of its faces. This tool will fit in the groove 26^a and may be secured in position in the same manner as the tool 26^b.

From the foregoing, I believe that the construction, operation and advantages of the invention may be clearly understood by those skilled in the art, and I am aware that changes may be made in the details disclosed without departing from the spirit of the invention as expressed in the claims.

What I claim and desire to secure by Letters Patent is:—

1. In a tool for finishing shafts and the like, a body having spaced bearing faces for a shaft, an adjustable member carried by the body having a bearing face thereon, a shaft engaging and finishing element supported in said body independently of the shaft engaged by said bearing faces, said element having a plane surface contacting with the work, means for guiding and feeding the finishing element, and means independent of the guiding and feeding means for moving the finishing element in a direction to effect the utilization of substantially the entire area thereof.

2. In a tool for finishing shafts and the like, a body having spaced bearing faces for a shaft, an adjustable member carried by the body and having a bearing face thereon, a shaft engaging and finishing element supported in said body independently of the

shaft engaged by said bearing faces, said element having a plane surface contacting with the work, means for guiding and feeding the finishing element, and means independent of the guiding and feeding means for moving the finishing element in a direction to effect the utilization of substantially the entire area thereof, the last mentioned means constituting a handle facilitating the manipulation of the tool.

3. A tool as claimed in claim 2 characterized in that the adjustable member is resilient whereby the pressure exerted by a shaft on the first mentioned bearing faces may be varied.

4. A tool as claimed in claim 2 characterized by the provision of means permitting the displacement of the adjustable member for facilitating the application of a tool to a shaft.

5. In a tool for finishing shafts and the like, a substantially U-shaped body designed to receive a shaft, spaced bearing faces on said body, an adjustable and displaceable shaft engaging member connected to said body for moving a shaft into frictional engagement with the bearing faces, a shaft engaging and finishing element associated with the body and having a plane surface contacting with the work, a feed and guide plate for said element, means for adjusting said feed and guide plate toward and away from the shaft, and means for moving said ele-

ment across said plate for utilizing substantially the entire area of the element.

6. In a tool for finishing shafts and the like, a body shaped to receive a shaft, spaced bearing faces on said body, an adjustable and displaceable shaft engaging member connected to said body for moving a shaft into frictional engagement with the bearing faces, a shaft engaging and finishing element associated with said body and having a straight surface contacting with the work, a feed and guide plate for said element, means for adjusting said feed and guide plate toward said shaft, and an adjustable handle carried by the body and engaged at its inner end with the finishing element for moving the latter across the feed and guide plate for utilizing substantially the entire area of the element.

7. A tool as claimed in claim 1 characterized in that the finishing element is replaceable end for end and face for face.

8. In a tool for finishing shafts and the like, a body including a plurality of angular members, one of said members constituting a bearing face for a shaft, a bearing block carried by another of said members, an adjustable bearing member, a shaft engaging and finishing element, and feeding and guiding means for said element carried by another of the body members.

In testimony whereof I hereunto affix my signature.

MICHAEL D. MALONEY.
